CLAIM

The ornamental design for a joint for a pipe connector, as shown and described.

DESCRIPTION

FIG. 1 is a front view of the joint for a pipe connector, being the same as the back view;

FIG. 2 is a left side view thereof, being the same as the right side view;

FIG. 3 is a top plan view thereof, being the same as the bottom plan view;

FIG. 4 is a cross sectional view along line 4—4 as shown in FIG. 1;

FIG. 5 is a perspective view thereof;

FIG. 6 is a reference view showing a state of being used thereof; and,

FIG. 7 is a reference separated perspective view showing a state of being used thereof.

The broken line showing of the pipe and pipe connector in FIGS. 6-7 is included for the purpose of illustrating environmental structure and forms no part of the claimed design.
